UNITED STATES PATENT OFFICE.

LANGFORD J. BOWNE, OF HOWARD BEACH, NEW YORK, ASSIGNOR TO WESTERN ELECTRIC COMPANY, INCORPORATED, OF NEW YORK, N. Y., A CORPORATION OF NEW YORK.

TELEPHONE SYSTEM.

Application filed September 7, 1922. Serial No. 586,615.

To all whom it may concern:

Be it known that I, LANGFORD J. BOWNE, a citizen of the United States, residing at Howard Beach, in the county of Queens, 5 State of New York, have invented certain new and useful Improvements in Telephone Systems, of which the following is a full, clear, concise, and exact description.

This invention relates to telephone systems and more particularly to switching systems wherein toll switching trunks are employed to establish telephone connections between distant subscribers.

It is the usual practice in establishing 15 connections between a toll line and a subscriber's station to employ a cord circuit at a toll operator's position and a toll switching trunk extending from the operator's position to a B operator's position at an office 20 in which the calling or called subscriber's station is located. Complete supervision of the connection in such systems is accorded the toll operator by the provision of supervisory signals in the cord circuit which indicates to the operator when either subscriber 25 answers, hangs up the receiver or flashes.

The supervisory conditions mentioned above introduce marginal conditions which necessitate an exactness of relay design.

30 In one system of the character mentioned, it has been customary practice to employ the sleeve or third wire of the line and cord circuits for selecting the type of supervision to be given by the cord circuit, and wherein, 35 such a condition prevails, it is the usual practice to employ three relays in the sleeve conductor to meet the necessary marginal conditions previously mentioned.

40 Objects of this invention are therefore to obviate the exactness of relay design required and to remove one of the above mentioned marginal conditions.

45 It is a further object of this invention to employ the ring conductors of the line and cord circuits used in such systems for selecting the type of supervision to be given by the cord circuit.

50 Another object of this invention is to maintain the supervisory selecting means disassociated from the line during the period of conversation.

A further object of this invention is to prevent the release of a relay due to a shunt circuit temporarily established therefor

during the existence of a locking circuit for 55 such relay.

In accordance with features of this invention, the system hereinafter to be described provides a cord circuit and a call circuit toll line wherein the ring conductors are employed for selecting the proper relays in the cord circuit for supervisory purposes, and thereafter the supervisory selecting apparatus is removed from the ring conductor.

60 Another feature of this invention resides 65 in the provision of locking circuits for two relays connected to the ring conductor, said circuits including resistance elements which are also included in temporarily established shunt circuits for the relays to prevent their 70 release.

75 A clear understanding of the invention will be had from the following detailed description and by reference to the accompanying drawings in which Fig. 1 shows a subscriber's station and a toll switching trunk; Fig. 2 shows a cord circuit embodying features of this invention, and the terminals of a call circuit toll line and of a ring-down toll line to which circuits the cord circuit 80 is particularly applicable, and Fig. 3 shows the remaining portion of the call circuit toll line and a subscriber's station.

85 Assuming that the subscribers on lines A and B are located at stations separated by a considerable distance and that telephonic connection is desired between these subscribers, the subscriber at A being the calling subscriber and the subscriber at B the called subscriber, the procedure is as 90 follows:

95 The subscriber at A initiates a call in the usual manner and causes the operation of line signals at a central office. Upon noting the illumination of a line lamp such as 112, the originating operator inserts the plug of an idle cord (not shown), associated with her position into the answering jack associated with the calling subscriber's line and operates her talking key to connect her telephone set with the calling subscriber in order to ascertain the nature of the call. Upon learning that a subscriber B is desired, the operator dismisses the calling subscriber and proceeds to establish the connection. The method and means employed whereby the originating operator signals other operators who may be called to com- 100 105

plete the connection, and the method of assigning the circuits to be employed in completing the connections are well known in the art and need not be described herein.

- 5 After the assignment of a toll switching trunk to be employed in establishing the desired connection, the local inward operator inserts the plug 100 of this toll switching trunk into the jack 101 of the line of the 10 calling subscriber A while an outward operator inserts the plug 201, associated with one end of the cord circuit, into the jack 202, which is associated with the toll switching trunk assigned by the local inward operator.

Upon insertion of the plug 100 into the jack 101 of the calling subscriber's line, a series circuit is established for relays 102 and 103, which may be traced from grounded 20 battery, through the winding of relay 103, over the sleeve contacts of plug 100 and jack 101 and thence to ground through the winding of relay 102. The operation of relay 102 disconnects signaling battery from 25 the subscriber's line A and releases relay 104 thereby extinguishing line lamp 112. The operation of relay 103 disconnects the operator's telephone set from the tip of the cord circuit and makes the tip conductor 30 continuous. Relay 103 also prepares a circuit for lamp 108 which may be traced from grounded battery, through the filament of lamp 108, the lower armature and front contact of relay 103, conductor 113 to the back 35 contact of relay 109, which relay has been operated upon the insertion of plug 201 into the jack 202. When plug 201 was inserted in jack 202 relay 203 operated over a circuit extending from grounded battery, 40 through the winding of relay 203, and thence to ground over the sleeve contacts of plug 201 and jack 202. Relay 203, in energizing, establishes an obvious circuit for relay 204. Relay 204, upon energizing, disconnects the 45 outward operator's telephone set busy test circuit from the cord circuit and makes the tip conductor thereof continuous. Relay 204, thereby establishes a circuit which may be traced from grounded battery, through the 50 right-hand winding of relay 109, conductor 114, normal contacts of relay 105, conductors 115 and 116, through the lower right-hand winding of repeating coil 107, over the ring conductor 117, the ring contacts of jack 202 55 and plug 201, the lower normal contact of ringing key 217, conductor 220, right-hand winding of retardation coil 205, through the winding of relay 206, left-hand winding of retardation coil 205, conductor 221, upper 60 normal contact of ringing key 217, through the armature and front contact of relay 204, over the tip contacts of plug 201 and jack 202, tip conductor 118, the upper right-hand winding of repeating coil 107, conductor 119, 65 the left-hand armature and back contact of

relay 105, conductor 120, and thence to ground through the left-hand winding of relay 109. Relays 109 and 206 energize in this circuit. Relay 109, in operating, prevents at its armature and back contact, the 70 illumination of lamp 108 over the circuit hereinbefore traced, in part. Relay 206, in operating, establishes an obvious circuit for lamp 207. The outward operator then connects her telephone set to the telephone 75 set of the operator at a distant toll office, at which office the line of the called subscriber terminates over a call circuit, which is not shown but is well known to those skilled in the art, and informs this operator that the 80 party on line B is desired.

This distant operator then assigns a call circuit toll line to the outward operator and inserts the plug 300 of the call circuit toll line into the jack 301 which is associated 85 with the called subscriber's line and the outward operator inserts plug 208 into jack 209 of the assigned toll line circuit. The insertion of the plug 300 into the jack 301 establishes a series circuit for relays 302 and 303 90 which may be traced from grounded battery, through the winding of relay 302, over the sleeve contacts of plug 300 and jack 301, and thence to ground through the winding of relay 303. Relay 303 operates and disconnects the line relay 304 from the subscriber's 95 line, thereby preventing the operation of line lamp 350. Relay 302 prepares a circuit for relay 318, which circuit is open at the armature and front contact of relay 315. 100

When the outward operator inserts plug 208 of her cord circuit into the jack 209 of the call circuit toll line, a circuit is established extending from grounded battery, through the winding of relay 212, the left-hand armature and back contact of relay 213, over the ring contacts of plug 208 and jack 209, over the ring conductor 330 of the call circuit toll line, the normal contacts of relay 306, conductor 331, and thence to ground through the winding of relay 307. It is to be noted that the sleeve circuit through relays 210, 211 and 306, up to this time, has been open at the contact of relay 307. Relay 212, in operating, transfers the 115 supervisory lamp 215 from the ring-down supervisory circuit to the third wire supervisory circuit which is one of the features of this invention. Relay 307, in operating, establishes a circuit extending from grounded battery, through the windings of relays 210 and 211, over the sleeve contacts of plug 208 and jack 209, the left-hand armature and front contact of relay 307, the winding of relay 306 to ground. Relay 210, being 120 marginal, does not operate in the circuit just traced. The circuit through the resistance element 309 which is normally bridged across the winding of relay 306 is open at the contact of relay 320 which relay oper- 125 130

ates from the middle contact of relay 307. Relay 211 operates in this circuit and establishes an obvious circuit for relay 213 and also establishes a locking circuit for 5 relay 212, which may be traced from grounded battery through the winding of relay 212, through the right-hand armature and front contact of relay 212, through the resistance element 214, and thence to ground 10 through the armature and front contact of relay 211.

The resistance element 214 is included in the locking circuit for relay 212 in order to prevent the short circuiting and therefore 15 the deenergization of relay 307. It will be noted that immediately upon the operation of relay 211, a momentary shunt about relay 307 may be traced from ground, through the winding of relay 307, conductor 331, 20 normally closed contacts of relay 306, conductor 330, ring contacts of jack 209 and plug 208, left hand armature and back contact of relay 213, right-hand armature and front contact of relay 212, resistance element 25 214 to ground at the armature and front contact of relay 211. Owing to the inclusion of resistance element 214 in the circuit just traced, relay 307 which would otherwise have been released by such shunt, 30 is maintained energized. Relay 213, in operating, disconnects the winding of relay 212 from the ring conductor of the toll cord. It is to be noted from the preceding description that the selection of supervisory 35 relay in the cord circuit is accomplished over the ring conductors of the cord and line circuits and after the selection has been made the selecting circuit is removed from the ring conductor. Relay 306, operating 40 in the circuit previously traced, removes the winding of relay 307 from the ring conductor of the call circuit toll line and establishes a locking circuit for this relay which may be traced from grounded battery, through 45 the resistance element 308, through the armature and front contact of relay 306, conductor 331 and thence to ground through the winding of relay 307.

When relay 306 is operating there is a 50 momentary circuit existing which may be traced from the grounded positive pole of battery, through resistance element 308, armature and make-and-break contacts of relay 306, conductor 330, ring contacts of 55 jack 209 and plug 208, left-hand armature and back contact of relay 213, winding of relay 212, through the positive pole of battery to ground. The two batteries are then 60 in opposition, but relay 212 is maintained operated owing to the presence of the resistance element 308 until the normally closed contacts of relay 306 are opened.

Relays 211, 213 and 306 operate in the order named to effect the proper functioning of relays 212 and 307, the latter re-

lays remaining locked over the locking circuits traced therefor. As a result of the energization of relay 307 a circuit is established from ground, front contact and inner right hand armature of relay 307, conductor 341, armature and contact of relay 319, conductor 352, winding of relay 320 to battery and ground. Relay 320 in operating opens the circuit of relay 324 to prevent the operation of relay 324 at this time. 70 Consequently the ground on conductor 341 is now also extended through the armature and back contact of relay 322, the back contact and armature of relay 324, winding of relay 321 to battery and ground causing the energization of relay 321. Relay 307, at its outer right-hand armature and front contact, establishes a circuit extending from grounded 75 battery, through the right-hand winding of retardation coil 310, the outer right-hand armature and back contact of relay 311, the lower right-hand winding of repeating coil 312, conductor 313 of the line, the lower left-hand winding of repeating coil 314, conductor 351, through the winding of relay 315, conductor 336, the upper left-hand winding of repeating coil 314, tip conductor 317 of the line, upper right-hand winding of repeating coil 312, conductor 337, the outer right-hand armature and front contact of relay 307, conductor 338, the inner right-hand armature and back contact of relay 311, and thence to ground through the left-hand winding of retardation coil 310. 80 Relay 316, which is bridged across relay 315, in the circuit just traced, being polarized, does not operate at this time. Relay 315 operates in the circuit just traced and completes the circuit previously prepared for 85 relay 318 by the operation of relay 302, which may be traced from grounded battery through the winding of relay 318, conductor 339, right-hand armature and front contact of relay 302, the left-hand armature and back contact of relay 305, conductor 460 and thence to ground, through the armature and front contact of relay 315. Relay 90 318 operates in this circuit and impresses ringing current from the source 340 over 95 the call circuit toll line conductors 317 and 313 and the windings of repeating coil 314, whereupon relay 319 is energized. Relay 319, in operating, opens the circuit through 100 the winding of relay 320, which releases, thereby closing the shunt around the winding of relay 306 including the resistance element 309, thus reducing the resistance of the sleeve circuit sufficiently to permit the 105 operation of marginal relay 210. Relay 210, in operating, establishes a circuit for the lamp 215 which extends from grounded battery, through the armature and front contact of relay 210, the filament of lamp 215 and thence to ground through the middle 110

left-hand armature and front contact of relay 212.

The illumination of the lamp 215 informs the outward operator that the line of the subscriber at station B has been connected to the call circuit toll line and she thereupon proceeds to ring the called station B by operating the ringing key 216, which impresses ringing current from the source 235 over the tip and ring contacts of plug 208 and jack 209 through the contacts of relay 321, and thence through the winding of relay 322. It should be noted that during the energization of relay 319 and the consequent de-energization of relay 320, that relay 324 becomes operated through the left hand armature and back contact of relay 320 so that the energizing circuit of relay 321 previously traced is opened thereby connecting the trunk conductors to the relay 322 so that this relay may now be operated. Relay 322, in operating, opens the circuit for relay 321 to prevent this relay from operating at this time, and establishes a circuit which may be traced from grounded battery, through the winding of relay 311, conductor 344, the armature and front contact of relay 322, conductor 341, and thence to ground through the inner right-hand armature and front contact of relay 307. Relay 311, in operating, reverses the polarity of the battery through the retardation coil 310, over the tip and ring conductors 317 and 313 of the call circuit toll line in order to operate the polarized relay 316. This reversal of polarity does not affect the operation of relay 315. Relay 316, in operating, establishes a circuit for relay 323, which may be traced from grounded battery, through the winding of relay 323, conductor 345, and thence to ground through the armature and front contact of relay 316. Relay 323 energizes and impresses ringing current from the source 340 over the armatures and front contacts of relay 323, over the tip and ring contacts of plug 300 and jack 301, and thence over the line to the subscriber's station B in order to ring the called subscriber's bell. When the operator releases ringing key 216, relay 322 releases and opens the circuit for relay 311. Relay 311, in deenergizing, again reverses the polarity of the battery on the tip and ring conductors 317 and 313 in order to release the polarized relay 316 which, in turn, interrupts the energizing circuit for relay 323, thereby removing the ringing current source 340 from the called subscriber's station. When the called subscriber removes the receiver from the hook an energizing circuit is established for relay 305. The circuit for relay 305 may be traced from grounded battery, through the winding of relay 305, conductor 354, over the ring contacts of plug 300 and jack 301, through the telephone apparatus at station B, over the tip contacts of jack 301 and plug 300, conductor 350, and thence to ground through the resistance element 367. Relay 305 opens the circuit for relay 318 which in turn removes the ringing current from the line and releases relay 319. The release of relay 319 establishes an operating circuit for relay 320 extending from grounded battery through the winding of relay 320, conductor 352, armature and back contact of relay 319, conductor 341, inner right-hand armature and front contact of relay 307 to ground. Relay 320 thereupon energizes and opens the shunt around relay 306, thereby increasing the resistance of the sleeve circuit to such an extent as to effect the release of relay 210 which at its armature and front contact opens the circuit for supervisory lamp 215. Relay 320 also opens the circuit of relay 324 which releases and closes the circuit for relay 321 which thereupon energizes and makes the talking conductors continuous.

A connection now exists between the called subscriber's line and the outward operator which may be traced over the tip and ring contacts of jack 301 associated with the called subscriber's line, the tip and ring contacts of plug 300, the upper and lower armatures of relays 323 and 318, the windings of repeating coil 314, over the tip and ring line conductors 317 and 313, the windings of repeating coil 312, the armatures and front contacts of relay 321, the tip and ring contacts of jack 209, the tip and ring contacts of plug 208, through the normal contacts of ringing key 216 and the normal contacts of talking key 218, conductors 240 and 241, and thence to the operator's telephone set through the contacts of key 234.

The calling subscriber is then rung by the operation of ringing key 217, which impresses ringing current from the source 242, over the tip and ring contacts of plug 201 and jack 202, the tip and ring conductors 118 and 117 of the toll switching trunk through the right-hand windings of repeating coil 107, and thence through the conductors 122 and 123, through the winding of relay 124. Relay 124 thereupon energizes and establishes a circuit extending from grounded battery through the right-hand winding of relay 105, conductor 127, through the winding of relay 125, conductor 126, and thence to ground through the armature and front contact of relay 124. Relay 125 thereupon energizes and connects ringing current from the ringing current source 128 to the tip and ring conductors of the cord, tip and ring contacts of plug 100 and jack 101 and thence over the subscriber's line loop to operate the bell at 130.

station A. The calling subscriber then removes the receiver from the switchhook and proceeds to converse with the called for subscriber.

5 The supervisory lamp 207 which indicates the response of the calling subscriber, is extinguished when this subscriber removes the receiver from the switchhook to cause relay 111 to operate. The circuit for relay 10, 111 may be traced from grounded battery through the winding of relay 111, the lower left-hand winding of repeating coil 107, through the armature and normal contact of relay 125, the ring contacts of plug 100 15 and jack 101 through the telephone apparatus at subscriber's station A over the tip contacts of jack 101 and plug 100, the upper armature and front contact of relay 103, the upper armature and normal contact of relay 125, and thence to ground through the upper left-hand winding of repeating coil 107. Relay 111 thereupon energizes and closes a circuit through relay 20, 105 which operates and removes battery 25 and ground connected through the windings of relay 109 from the repeating coil 107, the tip and ring conductors of the switching trunk, jack 202, plug 201, retardation coil 205 and the windings of relay 206. Relay 206 thereupon is deenergized and opens 30 the circuit for supervisory lamp 207.

The toll operator may converse with the called subscriber by the operation of splitting key 219, without the calling subscriber 35 hearing the conversation, and in a like manner by operating the splitting key 218, she may converse with the calling subscriber without the called subscriber hearing the conversation.

40 Upon the termination of the conversation, the called subscriber in replacing the receiver upon the switchhook releases relay 305. The closure of the left-hand armature and back contact of relay 305 completes a 45 circuit for relay 318 corresponding to that established when plugs 208 and 300 were inserted into jacks 209 and 301 respectively. Ringing current from source 340, thereupon 50 operates relay 319 which, in turn, releases relay 320 to re-establish the shunt circuit around relay 306 permitting marginal relay 210 to operate and cause the illumination of lamp 215 in the manner previously described. However, the illumination of lamp 55 215 at this time serves as a disconnect signal. Relay 320 in releasing also operates relay 324 and thereby releases relay 321 to render the talking conductors of the toll line discontinuous and to reconnect relay 322 to one 60 portion thereof. When the receiver is replaced upon the switchhook at the calling station, relay 111 releases to release relay 105 thus re-connecting battery and ground through the windings of relay 109 to conductors 117 and 118 for operating relay 206

to cause the illumination of lamp 207 to serve as a disconnect signal from station A.

The outward operator, noting the disconnect signals actuates listening key 234 and upon ascertaining that the conversation has ceased, removes plugs 201 and 208 from their respective jacks. The removal of plug 201 from jack 202 opens the circuit of and releases relays 203 and 109 to close an obvious circuit for lamp 108 and to open the circuit 70 of lamp 207. The illumination of lamp 108 serves as a disconnect signal to the toll switching trunk operator who thereupon removes plug 100 from pack 101, restoring to normal all apparatus of the line circuit including station A and the toll switching trunk.

The removal of plug 208 from jack 209 releases all operated relays of the cord circuit and releases relays 306 and 307 removing battery and ground from conductors 313 and 317 to cause the release of relay 315. Lamp 470 is then illuminated as a disconnect signal over a circuit traceable from grounded battery through the filament of lamp 470, right-hand armature and back contact of relay 305, conductors 471 and 473, the left-hand armature and front contact of relay 302, conductor 474 and the armature and back contact of relay 315 to ground. 85 The outward operator noting this signal removes plug 300 from jack 301, thus restoring to normal all remaining operated apparatus.

90 The following description is directed to the establishment of a connection between distant subscribers wherein a ring-down toll line is substituted for the call circuit toll line employed in the preceding description.

100 In order to show the functions of the toll cord circuit with a ring-down toll line, it is only necessary to describe how supervision is obtained and how the supervisory signal in the cord circuit is actuated on a ring incoming from a ring-down toll line as the 105 other operations are common to ring-down circuits and are well known in the art.

110 When the called subscriber is to be reached over a ring-down toll line, the outward operator inserts plug 208 into jack 230 and operates ringing key 216 which impresses ringing current from the source 235 to cause the signal at the distant station to operate. When plug 208 is inserted in jack 230, a circuit is established extending from grounded battery through the windings of relays 210 and 211, sleeve contacts of plug 208 and jack 230 to ground. The resistance of this circuit is so low as to permit the operation 115 of relays 210 and 211. Relay 212 does not operate in this instance as the ring conductor of the ring-down toll line is not grounded, a condition which is necessary to establish an energizing circuit for relay 212, 120 as described in connection with the call cir- 125

6

cuit toll line. Relay 211, in operating, establishes an energizing circuit for relay 213 which, in turn, at its left-hand armature and back contact, disconnects the winding of relay 212 from the ring conductor of the cord circuit and at its right-hand armature and front contact connects the tip conductor on the cord circuit to the operator's telephone set. Relay 210 establishes an energizing circuit for relay 231 extending from grounded battery, armature and front contact of relay 210, innermost left-hand armature and back contact of relay 212, conductor 246, winding of relay 231, and thence to ground through the armature and back contact of relay 232. Relay 231, in operating, prevents the illumination of the supervisory lamp 215 and the operation of relay 233 at this time.

When the operator at the distant office desires to signal the calling operator, she impresses ringing current upon the line by the operation of a ringing key similar to that shown at 216, whereupon relay 232, which is normally bridged across tip and ring conductors of the cord circuit, is energized and at its armature and back contact opens the circuit of relay 231. Relay 231, in releasing, establishes a circuit for supervisory lamp 215 extending from grounded battery, the armature and front contact of relay 210, the filament of lamp 215, the middle armature and back contact of relay 212, conductor 245, armature and back contact of relay 231, conductor 246, and thence to ground through the lowest normal contact of key 234. Relay 233 being bridged around lamp 215 operates and locks up, keeping the lamp lighted until the operator actuates key 234. Upon noting this signal, the operator operates key 234 to connect her telephone circuit to the cord circuit in a manner similar to that described in the first case.

From the foregoing description, it is obvious that the toll cord circuit functions with the ordinary type of ring-down toll line to select the proper relays for supervisory purposes as well as with the call circuit toll line shown in Fig. 3 and hereinbefore described.

What is claimed is:

1. In a telephone system, a line circuit, a cord circuit for connection therewith, each of said circuits having a plurality of conductors, a signaling device normally associated with one conductor of said cord circuit, means controlled over said conductor and the corresponding conductor of said line circuit and responsive to the interconnection of said circuits for disassociating said signaling device from said conductor of said cord circuit and associating it with another conductor of said cord circuit, and means for thereafter controlling said signal-

ing device over other conductors of said line and cord circuits.

2. In a telephone system, a line circuit, a link circuit for connection with said line, said circuits having talking and signaling conductors, a signaling device in one of said circuits, and means associated with one of the talking conductors of said circuits for transferring the device to the control of a signaling conductor of said circuits. 75

3. In a telephone system, a line circuit, a link circuit for connection therewith, said circuits having tip, ring, and sleeve conductors, a signaling device in one of said circuits, and a plurality of relays associated with the ring conductors of said circuits for preparing said signaling device for operation and thereafter transferring the control of said signaling device to the sleeve conductors of said circuits. 80

4. In a telephone system, a line circuit, a cord circuit for establishing a connection therewith, said circuits having tip, ring, and sleeve conductors, a signaling device associated with the ring conductor of said cord circuit, relays associated with the ring conductors of said circuits and responsive to the connection of said cord circuit with said line circuit for disassociating said signaling device from said ring conductor, and relays in said cord circuit for establishing locking circuits for said first mentioned relays for maintaining said relays disassociated from said conductor during the continuance of the connection of said cord circuit with said line circuit. 95

5. In a switching system, two relays, an operating circuit therefor, switching means controlled by a separate circuit to close locking circuits for said relays and to open said operating circuit, shunt circuits for said relays closed by said switching means after the closure of said locking circuits, and means in said shunt circuits for preventing the release of said relays due to said shunt. 105

6. In a switching system, a relay adapted to operate or hold upon the flow therethrough of currents of predetermined values, a circuit for operating said relay, switching means to close a locking circuit for said relay and thereafter open said operating circuit, and a shunt circuit established for said relay while said circuits are closed to reduce the amount of current flowing through the winding of said relay to said predetermined holding value thereby preventing the release of said relay. 115

7. In a switching system, a relay adapted to operate and to release upon predetermined values of current flow, a circuit for operating said relay, means to close a locking circuit therefor and thereafter to open said operating circuit, a shunt circuit for said relay established by said means while said circuits are closed to decrease the cur- 125

rent through the relay to a value in excess of said predetermined releasing value.

8. In a switching system, two relays, an operating circuit therefor, a second circuit closed by the operation of one of said relays, a plurality of relays included in said second circuit to close independent locking and shunt circuits for each of said first men-

tioned relays and to thereafter open said operating circuit, and means included in said shunt circuit to prevent the release of said first mentioned relays. 10

In witness whereof, I hereunto subscribe my name this 1st day of September, A. D., 1922.

LANGFORD J. BOWNE.
